UNITED STATES PATENT OFFICE.

MAURICE AUGUSTE EUGÈNE LEBLANC, OF SURESNES, NEAR PARIS, FRANCE, ASSIGNOR
TO COOPER HEWITT ELECTRIC COMPANY, OF HOBOKEN, NEW JERSEY, A CORPORA-
TION OF NEW JERSEY.

VAPOR ELECTRIC DEVICE.

1,161,485.

Specification of Letters Patent.

Patented Nov. 23, 1915.

Application filed March 18, 1913. Serial No. 755,131.

To all whom it may concern:

Be it known that I, MAURICE AUGUSTE EUGÈNE LEBLANC, a citizen of the Republic of France, residing at Suresnes, near Paris,

have invented certain new and useful Improvements in Vapor Electric Devices, of which the following is a specification.

This invention relates to vapor electric apparatus and more particularly to vapor electric lamps of the type for instance as described in the specifications of Letters Patent Nos. 923124 and 939708, in which the luminous portion or lighting tube of the container is provided at either end with receptacles open to the atmosphere and containing the mercury or other vaporizable conducting material employed, these receptacles as well as the lighting tube being preferably composed of quartz or other refractory transparent material.

Vapor electric lamps of the above general character are now well known, and the present invention has for its object to provide an improved construction which shall increase the useful life of the lamp, improve its efficiency of operation and enable the light thereof to be more effectively utilized for illuminating purposes than has hitherto been possible.

In order that the nature of the invention may be clearly understood a preferred form of lamp embodying the improvements constituting the subject-matter of the invention will now be described with reference to the accompanying drawings, of which—

Figure 1 is a view in front elevation, partly sectional, of the lamp, Fig. 2 being a plan view of the same.

Referring now to the drawings, the container 1 of the lamp comprises a lighting tube 2 in the form of a vertical loop, the end portions 3 of which are adjacent to one another at the base of the loop and are each connected to a mercury receptacle 4 provided with suitable tubular projections 5 through which the leading-in wires for connecting the lamp to a source of electric current are introduced.

The receptacles 4 above referred to are of cylindrical form having their axes slightly inclined to the horizontal so that those portions of each of the receptacles 4 to which the end portions 3 of the lighting tube 2 are connected, are somewhat lower than the op-

posite ends of the receptacles to which the tubular projections 5 containing the leading-in wires are attached.

The lighting tube 2 of the container 1 is provided on its upper surface with a pocket or cavity 6 formed in the wall of the tube 2, the latter of which is so arranged that its plane is inclined at an angle of approximately 45° with the plane containing the mercury receptacles 4 and the tubular projections 5 carrying the leading-in wires. The lighting tube 2 is also provided at or near its upper portion with a tubular extension 7 surrounded by a heating coil 21 connected up between the main lead and serving. The connections of the coil 21 are plain from the drawing. The conductor 22, the lead wire 23, and the side tube, 24, combined with the coil 21 explain the connections to vaporize the mercury or other liquid conducting material contained in the tubular extension 7 for the purpose of starting the lamp into operation.

The tubular projections 5 above referred to are arranged to be supported at their upper portions by a horizontal rod or tube 8 of quartz located above the lighting tube 2 and the container is mounted as a whole in a suitable frame arranged substantially in alinement with the mercury receptacles 4 and the portions 5 of the container in which the leading-in wires are located.

The tubular projections 5 are each provided with a conical or funnel-shaped partition 9 having an aperture 10 at its base and a smaller aperture 11 on one side thereof, the portions of the tubular projections 5 immediately below the partition 9 being formed into bulbs as shown in Fig. 1.

The leading-in wires as above stated are introduced through the tubular projections 5, one of these wires being indicated at 12. The wire 12 is located in a tube 13, the lower end of which is connected to one of the tubular projections 5 at a point below the normal level of the mercury within the container 1, the wire 12 passing through the open upper end of the tube 13 and projecting from the lower end of this tube through the aperture 10 into the tubular projections 5.

An auxiliary leading-in wire 14 is provided in one of the tubular projections 5, this wire being connected to the heating resistance surrounding the tubular extensions 110

7 in such a manner that when the level of the mercury in the projections 5 rises into engagement with the auxiliary leading-in wire 14 the heating resistance is short-circuited.

5 The leading-in wire 12 is located within the tube 13 in order to avoid any possibility of a permanent short circuit between the wires 12 and 14 due to the adhesion of oxidized mercury to the leading-in wires.

10 The mercury receptacles 4 are preferably each provided with a cylindrical body 15 of iron, nickel, nickel-plated copper or other suitable material which is not attacked by mercury and is at the same time a good conductor of heat. The bodies 15 replace a portion of the mercury which would otherwise be contained within the receptacles 4 and thus enable receptacles having a greater radiating surface for a given volumetric capacity to be employed, thereby facilitating the dissipation of heat generated in the lamp.

15 During the operation of the lamp above described bubbles of air or other gas which may be disengaged from the body of the mercury or other vaporizable material employed will, if occurring in the lighting tube 2, pass upward toward the top of the lighting tube and eventually enter the pocket or cavity 6 in which they are entrapped so as not to interfere with the efficient operation of the lamp. Any bubbles similarly formed in the receptacles 4 pass upward and outward into the tubular projections 5, and upon reaching the bulbous portions of the tubular projections 5 the bubbles will be entrapped therein.

20 As will be readily understood by those skilled in the art, it is a matter of considerable difficulty to form the apertures 10 at the base of the conical partitions 9 exactly to the required dimensions so that the cross sectional areas of the apertures 10 are not usually the same in the case of the conical partition in the two receptacles 5. The relative inequality in the cross-sectional areas of the passages constituted by the two apertures is evidently augmented owing to the reduction in the available area of these apertures due to the passage of the wire 10 therethrough. The inequality above referred to evidently tends to render the facility with which the mercury can rise and fall in the receptacles 5 different in the two receptacles, so that as the mercury passes into and out of the two receptacles as the lamp is started and extinguished, the greater impedance offered to the flow of mercury by one or other of the apertures 10 tends to cause the relative quantities of mercury in the two receptacles to become different from one another. The additional aperture 11 provided in each of the conical partitions 9 serves to prevent such inequality by provid-

25 ing an additional passage through the partition. This additional passage being a simple perforation in the wall of the partition its cross-sectional area can be more accurately determined than is possible in the case of the apertures 10 at the extremity of the conical partition.

30 The inclination of the plane of the loop constituting the lighting tube to the plane of the remainder of the container prevents the mercury receptacles at the base of the container and the vertical portions thereof from casting objectionable shadows and the frame carrying the container being as above described substantially in alignment with the mercury receptacles and the terminals of the lamp, are equally prevented from interfering with the general distribution of the light produced at the lighting tube.

35 The invention is evidently capable of being carried into practice in a variety of ways other than that described above and suitable modifications to meet the requirements of any particular conditions may be made without exceeding the scope of the invention.

40 What I claim is:—

1. The combination in a vapor electric device of receptacles for the vaporizable material, a tubular member connecting said receptacles, a tubular projection connected to each of said receptacles, a conical partition located within each of said tubular projections, and means for preventing an unequal accumulation of vaporizable material in said tubular projections.

45 2. The combination in a vapor electric device of receptacles for the vaporizable material, a looped member connecting said receptacles, tubular projections connected to each of said receptacles, a conical partition located in each of said tubular projections and a leading-in wire located in each of said tubular projections and passing loosely through said conical partition.

50 3. The combination in a vapor electric device of receptacles for the vaporizable material, a looped tubular member connecting said receptacles, a tubular projection connected to each of said receptacles and projecting vertically upward, leading-in wires and externally projecting tubes through which the said wires pass into the said tubular projections.

55 4. The combination in a vapor electric device of receptacles for the vaporizable material, a tubular member connecting said receptacles, an upwardly extending tubular projection located upon and in connection with each of said receptacles, a leading-in wire located within one of said tubular projections, a leading-in wire entering the other of said tubular projections below the normal level of the vaporizable material therein, a third leading-in wire also located in the last mentioned projection and means for pre-

venting a short circuit between the leading-in wires located in the tubular projection when the device is inoperative.

5. The combination in a vapor electric device of a pair of receptacles for the vaporizable material, an upwardly extending looped tubular member connecting said receptacles, an upwardly extending tubular projection for each of said receptacles, a perforated conical partition located in each of said receptacles and a leading-in wire passing through an aperture in the base of each of said partitions.
10. The combination in a vapor electric de-

vice of receptacles for the vaporizable material, a looped tubular member connecting said receptacles and bodies of material having a higher thermal conductivity than the vaporizable material located within said receptacles.

23 In testimony whereof I have hereunto set my hand in presence of two subscribing witnesses.

MAURICE AUGUSTE EUGÈNE LEBLANC.
